ATTORNEY

UNITED STATES PATENT OFFICE.

MICHAEL HEIDT, OF BROOKLYN, NEW YORK.

WINDOW GUARD.

Application filed February 2, 1927. Serial No. 165,273.

This invention relates to window guards in general and particularly to the kind adapted to be used when cleaning windows, and preventing the person cleaning and sitting on the window sill from falling out.

One of the objects of my invention is to provide a simple, inexpensive and effective device which may be readily attached to any existing window frame and removed therefrom when desired.

Another object of my invention is to provide within such guard, a construction of parts so arranged that they bear against the outer face of the window frame, and by doing so, prevent the guard from unintentionally moving from its place.

Another object of my invention is to provide means for adjusting the guard to any window or windows.

Another object of my invention is to provide in connection with such guard, means for limiting the movement of the various members to a certain maximum distance, at which point the guard parts are prevented from disengaging each other.

The foregoing and further objects will be more fully apparent from the following description and the accompanying drawings, forming part of this disclosure, and while not intended to limit this invention to the actual showing, illustrate some preferred forms of my idea.

Referring to the drawings, Fig. 1 illustrates a part of a window frame to which my device is attached.

Fig. 2 represents a cross sectional view through the lower part of a window frame to which my device is attached.

Fig. 3 is a perspective view of a preferred form of my device.

Fig. 4 is a detailed view showing the adjustable ends of the side members of my device.

Fig. 5 illustrates a partial detail view, in section, of a tubular member equipped with a spring actuated detent.

Fig. 6 is a cross sectional detail view of an attaching device adapted to be placed upon the window frame and serving for holding my device in place.

Fig. 7 represents a modified form of my attaching device in longitudinal and transverse sections and,

Fig. 8 is another modified form of my attaching device in elevation and in vertical cross sectional view.

Referring to the drawings, numeral 10 denotes a window frame resting preferably on a window sill 12. At the outer face 13 of the window frame will be seen (in Figs. 1 and 2), guard attaching members 14, a cross sectional view thereof being shown in Fig. 6. These attaching members are secured to the frame by means of bolts, screws, or nails, or in any other convenient manner, and they serve for receiving the depending legs 15 of end members 16 of my guard. These end members are bent at substantially right angles as indicated at 17, and their outer end is again bent so that it is substantially parallel with the face of the window frame.

The ends 18 of the side members are preferably provided with recesses 19 for a purpose explained later. Ends 18 of the side members telescope with the tubular central member 20. The latter is equipped with spring actuated detents 21 adapted to register with recesses 19 when the side members are drawn outwards to their extreme outer position. When detents 21 snap into recesses 19, they prevent the side members 16 from disengaging central member 20.

When it is desired to dismember my device, it becomes necessary to lift spring 22 to such a height as to permit detent 21 to clear members 16.

In Figs. 1, 2 and 6, I have shown brackets 14, while in Figs. 3 and 7, I have indicated a modified form of brackets at 23 which differ from brackets 14 in that they are of tubular design. They are held by a single screw 24 which is passed through a properly arranged aperture after having been slipped through opening 25.

In Fig. 8 is shown a still different form of a bracket 26 having a semi-cylindrical outer portion 27 and a flat back portion 28 provided with an aperture 29. The semi-cylindrical portion 27 is attached by means of side walls 30 to the back portion 28. This bracket is held by means of two or more screws for which holes 31 are provided.

As will be seen from Figs. 1 and 2, my device is extremely simple to apply to any existing window frame, by attaching the sockets of anyone of the designs shown to the upright outer face of said frame at about equal height. The side members 16 are adjusted to the proper length and the depending ends 15 of the side members are inserted into the sockets. The lower end of the depending portion of the side members bear

against the outer face of the window frame, thereby rigidly holding my device in the proper position and against unintentionally moving from the place first assumed. The 5 tubular member 20, with its spring actuated detents, holds ends 18 of the side members in the desired position and serves as back rest for the person cleaning the window.

It is obvious that the height of attachment 19 of my device may be arranged to suit the requirements in each individual case. Ordinarily, however, a standard may be adhered to for preventing the average person from falling backwards out of the window.

15 It is also obvious, that while I have shown my device attached to the window frame, that same can be readily removed by simply releasing the body pressure against the horizontal portion of my device and lifting the 20 vertical legs 15 from the sockets. Now the side members may be shoved together into the tubular central member and stored away, or the side members may be released from the central member by lifting up detents 21 25 and sliding out the side members from tubular member 20. Now all three pieces may be conveniently bound together and stored.

From the foregoing, it will be evident that 30 my device is a very inexpensive and effective construction and that it can be transferred from window to window where sockets have been attached at the outer face of the window frame.

While I have shown a specific form of my 35 device, be it understood that changes and improvements may be made within the scope of my invention for which I claim:

1. In combination with a window frame, 40 a window guard for safeguarding persons sitting on the window sill while cleaning

windows, said guard comprising a tubular central member, a pair of side members telescoping at one end with and adjustable within said tubular member and having depending ends adapted to bear against the outer 45 face of the window frame, and means, attachable to the latter, for receiving and firmly engaging said depending ends of the side members.

2. In combination with a window frame, 50 a window guard as per claim 1, the telescoping ends of said side members provided with recesses, said tubular central member having spring actuated detents registering with the 55 recesses provided in the side members when the latter reach their extreme outward position, thereby preventing said side members from disengaging said tubular member.

3. A window guard, comprising a plurality of adjustable, interconnected members, 60 two of said members having depending ends, means for attaching said two members to the outer face of a window frame in such a manner as to force their depending ends to bear against said frame, thereby preventing unintentional movement of said guard. 65

4. In combination with a window frame, 70 a window guard, comprising central and side members, adjustably interconnected with each other, said side members having depending portions adapted to form braces, means attachable to the outer face of said window frame for receiving said depending portions of said side members in such a manner, as to force the extreme ends of the depending portions against said frame. 75

Signed at New York in the county of New York and State of New York this 24th day of January, A. D. 1927.

MICHAEL HEIDT.
